PACKAGING CONTAINER FOR FOOD OR THE LIKE

Erwin H. Schimkat, 204 Nassau Blvd.,
Garden City, N.Y. 11530

Filed July 3, 1972, Ser. No. 268,521

Term of patent 14 years

U.S. Cl. D9—219   Int. Cl. D9—03

FIG. 1.

FIG. 3.

FIG. 2.

FIG. 5.

FIG. 4.

FIG. 1 is an isometric view of a packaging container for food or the like showing my new design;

FIG. 2 is a top view thereof;

FIG. 3 is a front elevational view thereof, with the rear and side elevational views being the same;

FIG. 4 is a bottom view thereof; and

FIG. 5 is an enlarged sectional view taken along line 5—5 of FIG. 2.

I claim:

The ornamental design for a packaging container for food or the like, substantially as shown.
